HERBERT E. MARSHALL AND JACOB SCHLAGEL, OF NEW YORK, N. Y., ASSIGNEES TO
HENRY W. AYLWARD, OF BROOKLYN, NEW YORK.

BOTTLE-CAPPING HEAD

964,926.

Specification of Letters Patent. Patented July 19, 1910.

Application filed December 5, 1908. Serial No. 466,060.

To all whom it may concern:

Be it known that we, HERBERT E. MARSHALL and JACOB SCHLAGEL, citizens of the United States, residing in the borough of Brooklyn, city of New York, in the county of Kings and State of New York, have invented a certain new and useful Improvement in Bottle-Capping Heads, of which the following is a specification, reference 5 being had therein to the accompanying drawings, forming part thereof.

Our invention relates to bottle capping machines, and particularly to machines for applying caps having a depending flange, 15 by pressing or clenching the flange in under the neck of the bottle.

It is well known in this art to apply the caps by rapidly spinning rollers, but several difficulties have been encountered with this 20 method, especially in using automatic feeders for the caps and charging apparatus for the bottles, in connection with the machine, since the feeder for the caps and the charging tubes interfere with the spinning operation. Furthermore it has proven extremely 25 difficult to apply sufficient pressure to the spinning rollers to secure a sufficiently strong seal.

One object of our invention is to obviate 30 these difficulties by eliminating the necessity for spinning and thereby the interference of the feeding and charging mechanism with the capping mechanism, and by exerting the full force of the pressure directly 35 on the flange.

Another object is to provide novel means 40 for compensating for variation in width of the beads of the bottle necks.

Still another object is to provide engaging means for the capping devices to insure 45 accurate and efficient engagement with the cap during the capping operation, and an effective forcing of the material of the cap against the bottle neck and under the shoulder thereof.

Other objects and advantages of our invention will appear from the following description. Broadly, our invention comprises a plurality of cap-setting plungers or 50 punches arranged so that they are adapted to be forced in simultaneously about the flange of the cap and to pinch it under the bead of the bottle neck and thus seal the cap on the bottle.

55 We shall now describe our invention with

reference to the accompanying drawings and shall thereafter point out our invention in claims.

Figure 1 is a plan view of our bottle capping head. Fig. 2 is a sectional elevation 60 of the same on the line $x-x$ of Fig. 1. Fig. 3 is a view similar to Fig. 2 on an enlarged scale with portions broken away, showing the parts in operative position. Fig. 4 is a detail plan view of the bottom plate, the 65 toggle links and the cap-setting plungers.

In the embodiment of our invention shown in the drawings, we employ four arcuate cap-setting plungers or punches 1, each a quarter circle and arranged to slide 70 together in a horizontal plane to form a complete circle. To reciprocate these plungers, we employ toggle joints with links 2 and 3, the former pinned to the cap-setting plungers 1 and the latter pinned to a bottom 75 plate 4 so as to bear against flanges 5 provided for this purpose. The bottom plate 4 is secured to a casting 6 and is spaced therefrom the thickness of the plungers 1, so that the adjacent walls serve as guides for the plungers. The casting 6 has four vertical bores 80 therethrough for the reception of toggle-operating spindles 7, which are linked to the toggle joints by the links 8. At the termination of these holes the bottom of the 85 casting 6 is provided with recesses as shown to allow movement of the toggle joints. The spindles 7 are surrounded by helical 90 springs 9, which bear at their upper ends against pins 10 extending through the spindles and bear at their lower ends against the shoulders 11 at the bottom of the bores of the casting 6, and tend to hold the spindles and toggles in raised position and consequently to hold the plungers 1 in retracted 95 position. The casting 6 is also provided with a central vertical bore in which is rigidly secured, as by a pin 13, a sleeve 12 in which slides the stem 14 of the plunger head 15. The stem 14 is provided with a 100 longitudinal slot, as shown, through which the pin 13 extends and which therefore permits the stem 14 to slide the length of the slot in the sleeve 12. At the lower end of the sleeve 12, the central bore of the casting 105 6 is enlarged to form an annular shoulder 16 against which the head 15 is adapted to engage as the stem 14 slides upward in the sleeve 12. A helical spring 17 in the sleeve 12 bears on the top of the stem 14 and tends 110

to hold the head 15 down as far as the slot and the pin 13 will permit, the position which it occupies in Fig. 2.

To actuate the toggle joints and the cap-setting plungers 1, it is evident that pressure must be exerted on the tops of the spindles 7 to force them down, and for this purpose a casting 18 is attached to the reciprocating plunger 19 of the bottle-capping machine, as shown, and is provided with a central bore which serves as a guide for the sleeve 12. The upper portion of this bore is enlarged and serves as a spring box for the helical spring 20, which bears on the top of the sleeve 12 and tends to hold it down and, consequently, to carry the sleeve 12 and the parts carried by it down with the plunger 19. The spanner nut 22^a in the top of the spring box, which serves as the top bearing for the spring 20, is screw-threaded as shown and, coöperating with corresponding threads in the spring box, is adjustable to adjust the tension of the spring 20. The sleeve 12 has an enlarged head 21, which is limited in its downward movement by the shoulder provided by the spring box and prevents the parts from separating. The spring box has a removable cap 22, thus providing means for disassembling the parts. The casting 18 has four vertical bores corresponding to those of the casting 6 and arranged so that they are in alinement therewith, and the castings are so spaced apart that in their extreme position the spindles 7 project slightly into the bores of the upper castings and act to keep the corresponding bores in line.

It is evident that, as the upper casting 18 is brought down with the plunger 19, if the lower casting is held stationary, as by a bottle, the spindles 7 will enter the bores of the casting 18; and to exert the necessary pressure on the spindles to actuate the cap-setting plungers 1, buffer disks 23 are held against a shoulder 24 by helical springs 25. Set-screws 26 are provided to adjust the tension of the springs 25. To facilitate the making of the bores and shoulders 24 in the casting 18, the casting may be made in two parts, as shown, and the parts then joined together.

It will appear from the foregoing that when a bottle is set in place with its cap against the head 15, and the plunger 19 and the parts carried by it are brought down, at the beginning of the movement all of the parts of the capping head move down relative to the head 15 for a short distance until the head 15 engages the shoulder 16. Thereafter the casting 6 and the parts carried by it are held stationary, and the spindles 7 are engaged by the disks 23, and the yielding pressures of the springs 25 begin to close in the plungers 1 about the flange of the cap, as shown in Fig. 3. The engaging edges of

the plungers 1 are provided with V-shaped grooves to insure a firm grip on the flange of the cap, and the flange of the cap has an outstanding edge which enters the grooves in the plungers as the plungers move inward. It has been found that the function of these grooves is of extreme importance in the successful operation of my bottle-capping head, and that they aid materially in making an effective seal, since, by firmly gripping the outstanding edge of the flange of the cap, they enable the plungers, in addition to pressing the flange in under the shoulder on the neck of the bottle, to also hold securely to the flange and draw the metal under the shoulder of the bottle and thus add to the effectiveness of the seal. The further downward movement of the plunger 19 is wholly utilized in direct pressure radially inward against the flange of the cap and a very effective seal is made. The pressure exerted is nevertheless that of springs and assures both that the cap flanges shall be forced fully inward and that the bottle shall not be injured. The pressure on the top of the cap is provided by the spring 20 so as to compress the cork to form a perfect seat.

To compensate for variation in width of the beads of the bottle necks, we employ a flat spring 27 under each of the plungers 1. These permit the engaging edges of the plungers to be carried down by the contour of the bead if the neck is thick and at the same time hold the plungers up to engaging position for beads not so wide. They also impart a yielding movement longitudinally of the bottle neck and in coöperation with the grooves in the plungers, enable the plungers to retain their grip and continue their pressure on the outstanding edge of the cap flange as the plungers force the flange in, and permit the metal of the flange to draw downward against the bottle neck and inward under the shoulder of the bottle neck. As soon as the plunger is reciprocated and the head carried up again, the parts are returned to their original position ready for the next operation.

It is obvious that various modifications may be made in the construction shown and above particularly described within the principle and scope of our invention.

We claim:

1. In a bottle-capping machine, a capping head comprising a plurality of arcuate cap-setting plungers adapted to close about the flange of the cap, toggle joints adapted to press the plungers to operative position, and means for actuating the toggle joints.

2. In a bottle-capping machine, a capping head comprising a plurality of normally retracted arcuate cap-setting plungers adapted to close about the flange of the cap, and toggle joints adapted to press the plungers to operative position.

3. In a bottle-capping machine, a capping head comprising a plurality of arcuate cap-setting plungers adapted to close radially inward about the flange of the cap, means 5 cooperating with the plungers to compensate for variation in width of the beads of the bottle necks, and means for actuating the plungers.
4. In a bottle-capping machine, a capping head comprising a plurality of normally-retracted arcuate cap-setting plungers adapted to close about the flange of the cap, resilient means coacting with the plungers to compensate for variation in width of the beads of the bottle neck, and toggle joints adapted to press the plungers to operative position.
5. In a bottle-capping machine, a capping head comprising a plurality of arcuate cap-setting plungers adapted to close about the flange of the cap, the plungers having engaging grooves on their operating edges, resilient means coacting with the plungers to compensate for variation in width of the beads of the bottle neck, and means for actuating the plungers.
6. In a bottle-capping machine, a capping head comprising a plurality of normally-retracted arcuate cap-setting plungers adapted to close about the flange of the cap, the plungers having engaging grooves on their operating edges, resilient means coacting with the plungers to compensate for variation in width of the beads of the bottle necks, toggle joints adapted to press the plungers to operative position and yielding means for actuating the toggle joints.
7. In a bottle-capping machine head, a cap-setting plunger movable radially inward and resilient means coacting therewith to permit the plunger to yield longitudinally of the bottle neck.
8. In a bottle-capping machine head, a cap-setting plunger adapted to engage the
- edge of the flange of the cap, and resilient means coacting with the plunger to compensate for variation in width of the beads of the bottle necks.
9. In a bottle-capping machine head for applying caps having a flange with an outstanding edge, cap-setting means for engaging the outstanding edge of the cap and forcing the flange in to grip against the bottle neck, and resilient means cooperating with the cap-setting means to permit such means to yield longitudinally of the bottle neck.
10. In a bottle-capping machine head for applying caps having a flange with an outstanding edge, arcuate cap-setting plungers for engaging the outstanding edge of the cap and forcing the flange in to grip against the bottle neck, and resilient means cooperating with the plungers to permit them to yield longitudinally of the bottle neck.
11. In a bottle-capping machine head for applying caps having a flange with an outstanding edge, cap-setting plungers adapted to engage the outstanding edge of the cap and force the flange in to grip against the bottle neck, and resilient means cooperating with the plungers to permit them to yield longitudinally of the bottle neck.
12. In a bottle-capping machine head, arcuate cap-setting plungers adapted to close radially inward to perform their capping operation, means for pressing the plungers inward, and resilient means cooperating with the plungers to permit them to yield longitudinally of the bottle neck.

In testimony whereof we have affixed our signatures in presence of two witnesses.
